A. W. ANKENY

MECHANICALLY OPERATED FIGURE TOY

Filed April 21, 1926

INVENTOR.

ARTHUR W. ANKENY.

BY

Richard B. Owen.

ATTORNEY.

UNITED STATES PATENT OFFICE.

ARTHUR W. ANKENY, OF INDIANA, PENNSYLVANIA.

MECHANICALLY-OPERATED FIGURE TOY.

Application filed April 21, 1926. Serial No. 103,647.

This invention relates to toys and in particular to a type to which mechanical motion is imparted so that the same will attract attention and will not only be amusing but will be useful in a variety of ways in which it may be employed.

A particular object of the invention is to provide a miniature toy fashioned after the traffic regulating officer and which shall have similar movements to an officer controlling traffic so that the moving parts thereof will draw attention.

A further object of the invention is to provide an intermittent means for operating the figure and also a stop and go semaphore in connection with the figure which will attract attention and thereby increase the value of the toy.

A still further object of the invention is to provide in combination with an attractive toy, an advertising device so that the latter will operate in unison with the movements of the figure of the toy so that said movements will draw attention to the advertising feature thereof.

A further object of the invention is to provide mechanism which will operate the figure and also the advertising device in proper sequence so that the movements of both will coordinate to produce the proper attention drawing effect.

To enable others skilled in the art to fully comprehend the underlying features of my invention that they may embody the same in the various modifications in structure and relation contemplated, a drawing depicting a preferred form has been annexed as a part of this disclosure and in such drawings, similar reference characters denote corresponding parts throughout all of the views, of which,

Figure 1 is a view in perspective showing the arrangement of my figure toy and showing also the advertising display device which is associated therewith.

Figure 2 is a sectional view in elevation arranged to show the interior mechanism which operates the toy.

Figure 3 is a side view in section showing the arrangement of the mechanism, the section being taken on the line 3-3 of Figure 2.

Figure 4 is a top plan view of the base of the toy, the top thereof being removed so that the interior mechanism can be seen, and

Figure 5 is a front view in elevation of a portion of the mechanism greatly enlarged to show the arrangement thereof.

Referring to the drawings in detail, 5 indicates the base or box portion of the toy which may be constructed of metal or other suitable material and in which may be housed the operating mechanism.

This housing 5 comprises the usual ends 6, top 7, bottom 8 and side walls 9, there being provided in the top 7, a suitable socket 10 into which is fixed the semaphore post housing 11 through which extends the post 12 which projects beyond the top of the housing 11 and carries at said projecting end, 60 the sign plate 13, which bears the legend "Stop" and transversely thereto, the sign plate 14, which bears the legend "Go". The indicator or semaphore post 12 is provided in its mid portion with an extension 15 which projects through a suitable slot in the housing 11 and has pivoted at its outer end as at 16, the arm 17 of the policeman's figure, the figure being indicated as at 18 and comprising the usual, hollow, metal figure construction employed in such toys to the body of which is suitably hinged as at 19, the said arm 17. It will be apparent therefore, that a movement in a revolving direction of the post 12 will cause the arm to hinge and swing with said extension 15 so that it will 70 be apparent that the figure of the officer is operating the semaphore. The figure 18 being hollow, as before stated, allows for the passage therethrough of a vertical figure post 20, which carries at its upper end, and has secured thereto, the head 21 of the figure, which, being attached to said figure post 20, is adapted to revolve therewith when said post is given a turning movement. The 75 post, adjacent its upper end, is provided with a cam member 22 over which is adapted to slide the cam rider 23. This cam rider 23 constituting the extended end of a pivot 24 which maintains the arm 25 of the figure in 80 position against the body and in lowered or raised position depending upon the position of the rider 23 on the cam 22.

It is evident that a revolving movement of the figure post 20 will revolve the pivot 24 through the medium of the cam rider and the arm 25 being secured to said pivot will raise and lower corresponding to the movement of said cam rider. The hand of the arm 25 carries a suitable baton or club 26.

The lower ends of the posts 12 and 20 are supported in suitable bearing plates positioned on the bottom 8 of the housing 5 and are adapted to revolve therein. The mechanism for causing the operation of the posts comprises a spring motor 27, which is mounted upon and operates the shaft 28, which is journalled in suitable standards 29 and has one end shaped to fit a suitable winding key 30, through the medium of which the spring 27 is wound to cause subsequent operation of the shaft 28, the latter carrying at its innermost end, the driving gear 30 which is fixed thereto and which 10 meshes with the intermediate gear 31 carried by but operating freely on the end of the ratchet shaft 32, which is journalled in the suitable standard 33 and also in one of the side walls 9 of the housing 5. This intermediate gear 31 drives the pinion 34 which is carried on the escapement shaft 35 and which operates the same when allowed to do so by the controlling escapement dog 36 and escapement wheel 37, the latter two 20 operating in the usual manner to prevent the rapid unwinding of the spring and abnormal operation of the gears and mechanism. The escapement shaft 35 is journalled in the standards 38. It will be seen, therefore, that the operation of the gear 30 is caused by the spring 27 when the same has been wound by the key 30 and said gear 30 30 operates the intermediate gear 31, the operation thereof being controlled by the escapement and pinion 34.

This intermediate gear 31 carries a finger 39 which extends beyond the periphery of said gear but is offset to clear the gear 30 during its revolutionary movement. The 40 finger 39, as shown in Figure 2 is in position to engage the arm 40 carried adjacent thereto on the semaphore post 12, said arm 40 extending over the gear 31 so that it will be engaged by the finger 39 to cause a turning of the post 12 through an arc of 90 degrees so that sign "Stop" will be revolved around until the sign "Go" is displayed. This finger 39 also during its revolving movement operates a similar arm 41 carried 50 on the lower end of the post 12 so that the movement imparted to the post 12 will be the opposite to that given to it when the finger 39 engages the arm 40.

The finger 39, therefore, operates the semaphore post alternately to display the signs "Stop" and "Go". In order to transfer the movement to the figure, I provide a link member 42, the ends of which are connected to the arm 41 and arm 43 carried at the lower end of the post 20, so that the movement of the post 12 is transmitted through the link 42 to the post 20 and causes simultaneous turning of the officer's head and lowering of his arm 25 when the sign is turned to the "Go" position. In connection with the

arm 41, I provide an additional link 44 which extends in the opposite direction from the link 42 and which is provided at its end with a piston 45, which operates in a cylinder 46, disposed in the housing 5. This cylinder 46 carries in one end thereof, a wind reed 47 through the medium of which a whistling sound will be produced upon a movement of the piston 45, this movement, being of course caused by the operation of the arm 42 in conjunction with the post 12. It will be evident, therefore, that upon every movement of the figure and the semaphore post, a sharp whistle will be produced which will simulate the whistle commonly 80 used by an officer in directing traffic.

In connection with the housing 5, I have provided on the front thereof a suitable box or container 48 which comprises a bottom 49 and a front wall 50 which extends half way across said container 49 and in which is pivoted as at 51, the outer end of the shaft 32. This shaft 32 in that portion which lies within the container or housing 48 is provided with a sleeve 52 which is loose on the shaft 32 and which also carries loosely the projected ends of display cards 53, which are hidden from view by the wall 50 but which, when turned to the position shown in Figure 1 are in position for display and may bear any suitable legend thereon suitable to the business with which said toy or display device is identified, it being of course understood that this device is not merely a toy but can be used and embodied in a large 100 model to attract attention to advertising medium displayed on the cards 53, and it is necessary therefore to provide a card throwing device which will operate the cards one after another to successively display them in 105 the open portion of the container 48 and to this end, I provide on the front wall of the housing 5, a bracket 54 which carries a suitable jack shaft 55, the latter having disposed at one end thereof, an operating pinion 56, which is in engagement with a tooth operating member or gear 57, which is secured to and operated by the shaft 32 so that the revolving movement of the gear 57 will cause operation of the shaft 55 to throw a 110 card throwing rack 58 which is secured to the shaft 55 and operates through a suitable opening in the wall of the housing 5 to cause the throw-over of the card 53 positioned behind the wall 50 of the container 48. This 115 rack 58 is formed with an eccentrically disposed edge portion 59 in which are formed the teeth 60, these teeth coming into contact with successive cards as the rack 58 is operated in the direction indicated by the arrow in Figure 3. It will be evident, therefore, that the operation of this card throwing rack through the opening in the side wall of the housing 5 will bring each of the 120 teeth successively into contact with the low- 125

er edge of a card and will gradually throw the cards over to the position shown in Figure 1.

In order to cause this throw of the rack 58, which operates through the slot 51 in the housing 5 I provide on the shaft 32, a ratchet wheel 62 over which travels the pawl 63, loosely pivoted on the operating arm 64, which is journalled on the shaft 32 and has free movement therearound when the same is actuated through the medium of a suitable link 65, the end of which is pivoted as at 66 to the end of an arm 67 secured on figure operating post 20. It will be evident, therefore, that a turning movement of the post 12 as has heretofore been explained, will cause a turning movement of the post 20 and this in turn will cause, through the link 65, the operation of the shaft 32 intermittently, to cause the rack 58 to move outwardly and upwardly to throw the card. Particular attention is directed to the fact that the slot 61 is located adjacent the offset portion of the card through which the shaft or sleeve 52 passes so that a very slight upward movement on the tab of the card will only be necessary to throw the same over to display position.

In order to eliminate the throw-over of the card when the same is not desired, I provide on one of the brackets 38, a boss 68 through which passes the pawl throw off rod 69, the end 70 of which is disposed exteriorly of the casing 5 and when manipulated to the position shown in the dotted lines in Figure 2 will prevent the pawl 63, when it has downward movement, from engaging the next successive tooth on the ratchet 62, thereby preventing operation of the shaft 32 and throw-over of the card.

When the cards have been thrown over and it is necessary to restore them to their original position, and to accomplish this, I provide a card throwing foot 72 which is of substantially U-shaped formation and is loosely mounted on the shaft 32 and, as seen in Figure 5, is provided with a toe portion 73 and sleeve 74, the latter of which carries the extended lip 75 which rests upon the end of an arm 76 which is pivoted as at 77 to the side wall of the housing 5 and overlies at its mid portion, the pivot 78 which retains another scissor-like lever 79 in connection therewith against the side wall of the housing. This lever 79 having an extended portion 80 which underlies said lever 76 and causes a throw-up movement of the same when the end of the lever 79 is engaged by the projection 81 carried by the gear 57. It will be evident, therefore, that the cards are thrown over to the display position once in every revolution of the gear 57 and that when the extension 81 thereon revolves around until it contacts the end of the lever 79, it will cause a throw-up of the lever 76,

whose end engages the finger 75 and the throw-up of the lever 76 will consequently cause the card returning foot 72 to kick up to throw the cards back behind the wall 50 of the container 48, the position of the foot 72 being returned to normal automatically when the extension 81 of the gear 57 rides over the end of the arm 79, as will be apparent from inspection of Figure 5.

It will be evident, therefore, that I have provided a unique and amusing figure toy, which can be used not only to keep children amused but which can be used in a variety of ways to call attention to advertising through the medium of motion which is the most effective means of display advertising. It is also evident that I have provided a toy having few parts and one which can be easily made up and will efficiently perform the function for which it has been designed.

While I have illustrated and described my invention with some degree of particularity, I realize that in practice various alterations therein may be made. I therefore reserve the right and privilege of changing the form of the details of construction or otherwise altering the arrangement of the correlated parts without departing from the spirit of the invention or the scope of the appended claims.

Having thus described my invention, what I claim as new and desire to secure by United States Letters Patent is:—

1. A toy comprising a semaphore, a figure representing a traffic officer, means for operating said semaphore, a connection between said figure and said semaphore, a movable arm on the figure, a movable head on said figure, and means operated by said semaphore operating means for moving the head and arm of said figure simultaneously.

2. A toy comprising a revolvable semaphore, a figure adjacent said semaphore, one arm of which is adapted to have contact therewith, a revolvable head on said figure, means for revolving said head and said semaphore simultaneously, and means associated with said head revolving means for operating the other arm of said figure.

3. A toy comprising a revolvably mounted traffic signal, a figure representing a traffic officer adjacent said signal, one of the arms of the figure being pivoted and extended towards said signal, means for revolving said signal, a pivotal connection between the arm of said figure and said signal whereby the arm may partake of the revolving movement of said signal, another arm pivoted on said figure and means for operating said arm with said signal simultaneously.

4. A display device comprising a revolvable signal post, a figure simulating a traffic officer, means for revolving the post, a connection between the post and the figure

whereby it appears as though the figure was turning the signal post, means for causing intermittent operation of said post revolving means, an audible signal, and a connection between the signal and the post operating means whereby the signal is sounded upon a revolving movement of the post.

5. A toy comprising a visual signal, a figure simulating a traffic officer, a movable

arm on said figure, an audible signal, a 10 mechanically operated mechanism for operating the visual signal and the figure arm, and means controlled by said mechanism for operating the audible signal upon operation of said visual signal. 15

In testimony whereof I affix my signature.

ARTHUR W. ANKENY. [L.S.]
